UNITED STATES PATENT OFFICE

THOMAS G. HITT, OF SEATTLE, WASHINGTON

MANUFACTURE OF FIRECRACKERS

Application filed January 12, 1931. Serial No. 508,218.

This invention relates to pyrotechnics; and more particularly, to a new method of manufacturing and assembling firecrackers of the type covered in my Patent No. 1,253,359, patented January 15, 1918.

The prime object is to construct a firecracker consisting of a bag filled with an explosive placed in a tube intermediate the ends of said tube, the ends of the tube being open in such a manner that there will be no chance for wrinkles or twisted bags which sometimes occurs when the bags are filled independent of the tube and afterwards forced therein. Heretofore the tubes have been rolled in a certain length and diameter, and the bags formed independent of the tube and filled with the explosive, the fuse placed in the bag and the same tied, after which the bag is forced into the tube. As these bags are hand made and filled, it is almost impossible to have a uniform bag that exactly fits the tube. Invariably the bag is either slightly undersize or oversize. Where the bag is undersize, an inferior detonation results as the gases have a chance to escape from the confining bag into the air space between the tube and the bag before the detonation occurs. In the case of the oversize bag, the same becomes twisted or bent in being forced into the tube which may result in a burning instead of a detonation, or a plurality of weak explosions.

By placing the empty bag in the tube on a former and then filling the same with the explosive after the former has been removed, a uniform tight fit is always obtained which results in a loud detonation and a very superior structure.

Another object is to provide a firecracker of the type described herein, the bag containing the explosive charge being always closely adjacent the inner wall of the tube.

Other objects will be disclosed in the specification and claims forming a part of this application.

In the drawing:

Figure 1 is a vertical section showing the bag slightly projecting from the open ended tube, with the former extending therefrom preparatory to filling;

Figure 2 is a vertical section showing the bags still projecting from the tube with fuses inserted therein, the mouth of the bag tied; and

Figure 3 is a vertical section of the finished article showing the bag in dotted lines.

Referring to the drawing in which similar parts are designated with like numerals:

Numerals 4 designates a tube or casing of light wrapping material having open ends 5 and 6. Within the tube 4 is placed a bag 7, formed of paper on a former 14 having one end 8 closed by turning the same up along one side of the bag and spaced from the open end 5. The upper end 9, which is open, projects above the open end 6, as shown in Figure 1. Explosive material 10, preferably a flash material similar to that disclosed in my Patent No. 1,253,597, is placed in the open mouth of the bag 7, a fuse 11 being placed therein, after which the mouth of the bag is securely tied. The bag 7 is then pushed down into the tube 4 so that the explosive charge will be spaced from the open ends 5 and 6 of the tube 4. A settle 12, having a stud 13 is used to hold the tube 4, the end 6 being placed over the stud 13.

As actually made, the tubes 4 are formed either on tube-bending machines or by hand and labelled, and then set up on settles 12. The bags 7 are formed on formers 14 of the exact diameter of the tubes 4, ends 8 being formed closed on the formers and thrust into the tubes 4. The studs 13 extend up into the tubes 4 a sufficient distance so that when the ends 8 contact with the studs 13, the open ends 9 will extend above the ends 6 of the tubes 4. Measuring spoons, not shown, containing the correct amount of explosive, are then used to fill the bags.

Since the bags have been formed on formers the bottom end of the bag being turned up along one side and inserted in the tube while still on the former, there will be no wrinkles present and the sides of the bag will be in close proximity to the sides of the tube. The filling of the bag with the explosive serves to hold the side of the bag extended against the inner walls of the tube 4. The fuses 11 are then inserted in the explosive

and the mouths of the bags 7 are secured with thread or similar securing means, after which the tubes 4 are removed from the settles 12 and the bags 7 thrust further into the tubes 4 so that a space is left both at the top and bottom to conform with the patent structure set out in my Patent No. 1,253,596.

It is obvious that under this method of constructing my firecracker that there is no chance of wrinkles or twisted bags, and further, that a much superior cracker is formed.

What I claim is:

1. Method of making firecrackers consisting in inserting a flexible bag in a tube to a distance short of the bottom of said tube, and filling said bag with an explosive material for forcing the sides of the bag against the sides of the tube with pressure sufficient to hold the bag in position.

20 2. Method of making firecrackers consisting in inserting the bottom portion of a bag into a tube, leaving the mouth projecting above the top of the tube, filling the bag with an explosive material for forcing the sides of the bag against the sides of the tube with pressure sufficient to hold the bag in position, inserting means adapted to ignite the explosive material in the mouth of the bag, closing the mouth of the bag and forcing the bag into an intermediate position in the tube so that there is a space above and below said bag.

3. Method of producing firecrackers of the open ended type consisting of placing one end of an open ended tube on the projecting portion of a settle, inserting the bag in the opposite end of the tube until the bottom portion contacts with the projecting portion of the settle, filling the bag with an explosive so that the sides of the bag contact with the interior walls of the tube with a sticking frictional pressure, inserting means for igniting the explosive in the mouth of the bag and closing the same, removing the tube from the settle and forcing the bag into the tube so that there is a space above and below the explosive contents of the bag.

4. Method of producing firecrackers of the open ended type consisting of placing a tube on a settle, forming a bag on a former, inserting the bag on the former into the tube, removing the former from the bag, filling the bag with an explosive for forcing the sides of the bag against the sides of the tube with pressure sufficient to hold the bag in position, inserting means for igniting the explosive in the mouth of the bag and closing the same.

5. Method of producing a firecracker of the open ended type consisting of placing one end of an open ended tube on the projecting portion of a settle, forming a bag on a former, inserting the bag on the former to the opposite end of the tube until the bottom portion contacts with the projecting portion 65 of the settle, removing the former from the

bag, filling the bag with an explosive material for forcing the sides of the bag against the sides of the tube with a sticking frictional pressure sufficient to hold the bag in position, inserting means for igniting the explosive in the mouth of the bag and closing the same, removing the tube from the settle and forcing the bag into the tube so that there is a space above and below the explosive contents of the bag.

In testimony whereof I affix my signature. 75
THOMAS G. HITT.
